UNITED STATES PATENT OFFICE.

JAMES F. RALEIGH, OF CHICAGO, ILLINOIS, ASSIGNOR TO PINES MANUFACTURING COMPANY, OF CHICAGO, ILLINOIS, A CORPORATION OF DELAWARE.

DESIGN FOR AN AUTOMOBILE-RADIATOR FRONT.

55,435.

Specification for Design.

Patented June 8, 1920.

Application filed March 1, 1920. Serial No. 362,561. Term of patent 14 years.

To all whom it may concern:

Be it known that I, JAMES F. RALEIGH, a citizen of the United States, residing at Chicago, in the county of Cook and State of Illinois, have invented a new, original, and ornamental Improvement in Design for Automobile-Radiator Fronts, of which the following is a specification, reference being had to the accompanying drawings, forming part thereof.

In the drawings,

Figure 1 is a front elevational view of an automobile radiator front embodying my new design, and

Fig. 2 is a side elevational view of the same.

In each of the figures the outline of the automobile radiator to which the device of my invention is applied is indicated by dotted lines.

I claim:

The ornamental design for an automobile radiator front, as shown.

In witness whereof, I hereunto subscribe my name this 23 day of February, 1920.

JAMES F. RALEIGH.

Witnesses:

ANDREW WINTERCORN,
EDNA V. GUSTAFSON.
